PROGRAM TRANSMISSION OVER WIRES.

Application filed November 11, 1922. Serial No. 600,356.

This invention relates to systems of communication and more particularly to systems for disseminating news, information, music or the like.

- 5 Various schemes have been proposed heretofore for program transmission. The only one of these schemes which has been exploited to any extent is radio broadcasting, that is, the broadcasting of news, information or entertainment by means of radio telephone equipment so that persons provided with suitable radio receiving sets tuned to the proper wave length may receive the transmitted entertainment or the like.
- 10 Realizing the inherent limitations of radio broadcasting, proposals have been made to use existing wire systems, such as telephone, telegraph or power networks for program distribution purposes by transmitting carrier frequencies over such existing power or communication lines. Such a method, however, would be extremely expensive as well as complicated, as it involves a very considerable reorganization of the telephone
- 15 plant or power plant, and requires the use of quite complicated and expensive apparatus.

The ordinary telephone plant, however, offers unusual facilities for program distribution purposes by the use of ordinary telephonic methods and without the employment of any high frequency or carrier methods of signaling. When it is realized that the average subscriber's telephone set is in use for telephonic purposes only during an extremely small part of the time it becomes apparent at once that if the telephone line, during its idle periods, could be used for disseminating news, information or entertainment, the plant could be used much more economically and the information or the like to be distributed could be transmitted to the subscriber in the simplest manner possible. It may further be observed that the average subscriber to a distributing service, particularly a service for distributing entertainment, would only desire to avail himself of the service during the late afternoon or during the evening, at which times the average subscriber's telephone is only used for social purposes and is rarely or never used for business calls.

Having these circumstances in mind, it is

proposed by this invention to provide simple, practical and economical arrangements by which news, information, music or other forms of entertainment may be transmitted at ordinary telephonic frequencies from a central program distributing station over subscribers' telephone lines. It is also proposed by this invention to provide a system whereby the telephone subscriber may receive the entertainment service without interfering in any way with the use of his line for ordinary telephone purposes. This invention also renders available a program distributing system in which the apparatus not only at the central station but more particularly at the subscriber's station, will be extremely simple and economical and yet 70 efficient.

It is, of course, possible to so arrange the circuit for accomplishing these results that the connection and disconnection of the program apparatus to the subscriber's line will 75 be directly under the control of the subscriber. The circuit arrangement of the present invention, however, is such that the program equipment may be connected to the subscriber's line by an operator at a special 80 switching point. This enables the subscriber either to contract for the entertainment service for certain periods of the day or he may obtain the service at any time of the day by calling the operator and asking for 85 it.

The invention may now be more fully understood by reference to the following detailed description thereof when read in connection with the accompanying drawing, in 90 which Figure 1 is a circuit arrangement embodying the principles of the invention and Figs. 2 and 3 illustrate modifications.

Referring to Fig. 1, L designates an ordinary telephone subscriber's line terminating at one end at a subscriber's station A and at the other in a central office B. At the station A, the usual form of telephone set 10 is provided for ordinary telephonic purposes and a supplemental key K is provided for associating with the line a program receiving equipment comprising a loud speaking receiver 11 and other apparatus to be described later.

At the central station B, the line terminates at an operator's position of the switch-

board in the usual type of switching jack J, whereby telephonic communication may be established through the cord circuit C between the line L and other lines terminating at the exchange. Normally, the line is connected with the jack J over the contacts of the marginal relay 12, which, when energized, is so arranged as to disconnect the line from the jack J and connect it to a jack J' through which a connection may be made to a program station (not shown) through a cord or trunk C' terminating in a plug P'.

As the program station is not normally connected to the line L, the subscriber, in order to avail himself of the service, may either have a contract arrangement whereby the special operator in charge of the program equipment may connect the program station to the line during a given period of the day by inserting the plug P' in the jack J', or the subscriber may call up the operator at the regular switchboard in the usual manner and the operator, upon being informed that a program connection is desired, may instruct the special operator to insert the plug P' in the jack J'. In order to signal the regular operator the usual line relay LR is provided at the regular switchboard. This line relay LR is marginal and does not operate through the high impedance connection established by the key K, and will only operate when the line is closed through the low impedance telephone set 10 by taking the receiver from the switchhook. A similar line relay LR' is provided in connection with the cord circuit C' and this second line relay jointly controls the circuit of the marginal relay 12 with the cut-off relay COR at the regular operator's position.

At the subscriber's station, the transformer 14, which serves to associate the loud speaking receiver 11 with the line, is provided with a condenser shunted by the high resistance winding of the polar relay PR. Owing to the high resistance of the latter, when the key K is thrown, insufficient current flows through the bridge, including the windings of the line relays LR and LR', as the case may be, to operate said relays. The polar relay PR controls a relay 16, whereby the loud speaking receiver 11 may be disconnected from the line even though the key K is actuated. The polar relay PR is so poled as to energize the relay 16 only when battery is supplied to the line from the cord circuit C, used in establishing regular telephone connections, the battery connections through the windings of the relays LR and LR' being reversed with respect to the cord circuit. Consequently, the relay PR disconnects the loud speaking receiver 11 only when the operator inserts the plug of the cord circuit C into the jack J to establish an ordinary telephone connection.

A low resistance relay 17 is included in series with the subscriber's set 10, said relay operating to disconnect the polar relay PR and loud speaking receiver 11 from the line L through an auxiliary relay 18 whenever the subscriber takes down the receiver to use his set either for making or answering an ordinary telephone call. This arrangement is provided so that the program receiving equipment will be disconnected under these circumstances even though the subscriber should fail to restore the key K.

The detailed operation is as follows: Assuming that the subscriber at station A desires to receive the entertainment service he removes the receiver from the switchhook, thereby closing the line circuit to operate the line relay LR, the line relay in turn causing the line lamp to glow. The relay 17 at the subscriber's station is operated in series with the line relay LR and functions to disconnect the loud speaking receiver 11 and associated equipment from the line independently of the key K. When the operator at the regular switchboard observes the call signal, she will answer the call by inserting the plug of the cord circuit C in the jack J, thereby energizing the cut-off relay COR, which disconnects the line relay LR from the line and extinguishes the signal. Upon being informed that a program connection is desired the operator will inform a special operator at the program multiple that a program connection is desired upon this particular line.

In practice, different programs may be transmitted at the same time and if the subscriber has asked for connection with a station sending out a particular program, the operator at the program multiple will insert the plug P' of the cord circuit C' connected with the proper program station into the jack J'. The operator at the regular switchboard position in the meantime will instruct the subscriber to hang up his receiver and will withdraw the plug P from the jack J. The cut-off relay COR is de-energized upon withdrawing the plug P and a circuit is completed over the right-hand back contact of the cut-off relay COR through the winding of the marginal relay 12, over the sleeve conductors of the jack J' and the plug P' and back contact of the marginal relay LR' to battery. The marginal relay 12 is now energized and disconnects the line L from the jack J and connects it to the jack J' so that a connection is extended over the cord circuit C' to the program station. As the subscriber has already hung up his receiver the marginal relay LR' will not be energized and the relay 17 at the subscriber's station, which was also deenergized by hanging up the receiver, will release the relay 18 so that the loud

speaking receiver 11 and associated apparatus may be connected with the line by actuating the key K.

The subscriber may now receive the program transmission by throwing the key K, thereby completing a circuit through the winding of the polar relay PR, over the normal contacts of the relay 18, over the make contacts of the key K, over the line L, make contacts of the relay 12, jack J', plug P' and through the windings of the marginal relay LR'. The relay LR' is not energized over this circuit as insufficient current flows through the high resistance winding of the polar relay PR. The latter relay, upon the other hand, is not effectively energized because the current flow is not in the proper direction to shift its armature. The circuit is now in such condition that the loud speaking receiver 11 will be actuated by the currents transmitted from the broadcasting station. During this condition of the circuit a busy tone is applied over the lower front contact of the relay 12 to the sleeve of the jack J at the regular switchboard to inform the operator that the line is being used for entertainment purposes.

If, while the line is thus in use, a sufficiently urgent call should come into the central switching office for the line L, the operator at the jack J may disregard the busy tone and insert the plug of the cord C in the jack, which thus completes a circuit over the sleeve of the jack J through the cut-off relay COR. The cut-off relay at its right-hand contact opens a circuit of the marginal relay 12, which is at once deenergized and disconnects the line L from the program station over the jack J' and connects the line to the jack J for receiving the incoming call. The direct current now being supplied from the cord circuit C is in such a direction as to actuate the polar relay PR to close the circuit of the relay 16, which at once disconnects the loud speaking receiver 11 from the transformer 14. The relay 16 is locked over its right-hand front contact, right-hand back contact of relay 18 and lower make contact of key K, so that said relay 16 will be held up independently of the polar relay.

The subscriber may now be rung in the usual manner by the operator and upon removing the receiver from the hook the talking circuit will be established to the central office. Direct current from the central office battery flows through the cord circuit over the subscriber's line and through the relay 17, this relay being energized as long as the receiver is removed from the hook. The relay 17 completes a circuit of the relay 18, which disconnects the program receiving apparatus from the line independently of the key K, and at its right-hand contact opens the locking circuit of the relay 16, which is restored to normal. At the end

of the conversation, the subscriber may hang up his receiver, thereby giving the usual disconnect signal and deenergizing the relay 17, which (if key K has not been restored) again connects the polar relay PR to the line. The current through the polar relay is in such a direction as to attract its armature and thereby complete a circuit to energize and lock up the relay 16. As soon as the operator withdraws the plug of the cord C from the jack J, the cut-off relay COR is deenergized, thereby causing the relay 12 to be energized and again connect the line L to the central program station over the jack J'. The direction of the battery current over the line L is now reversed so that the armature of the polar relay PR falls off but relay 16 remains locked up. In order that the communication from the program station may be again received the key K should be restored to unlock the relay 16 and should then be again actuated.

If, while the line is being used for receiving the distributed information, the subscriber should desire to use the line for establishing a telephone call, the receiver may be removed from the hook, thereby again energizing the relay 17 and, owing to the decreased resistance through the telephone set, energizing the relay LR' in the cord circuit C'. The relay 17 actuates relay 18 to disconnect the program receiving equipment independently of the key K. The relay LR', on the other hand, shifts its armature so that the circuit of the marginal relay 12 now passes through the high resistance left-hand winding of relay LR'. This causes the marginal relay 12 to be deenergized, thereby disconnecting the line L from the jack J' and connecting it to the jack J. The circuit of the line relay LR is now completed so that the operator at the regular switchboard will be called and may establish the desired connection in the usual manner through the cord circuit C. The insertion of the plug P of the cord C in the jack J causes the cut-off relay COR to hold open the circuit of the marginal relay 12 and release relay LR'. At the end of the conversation, the subscriber may hang up his receiver, thereby restoring the line to the condition for program reception in the manner already described.

When the subscriber no longer desires to receive the entertainment service he will simply restore the key K, thereby disconnecting the loud speaker and associated apparatus from the line. The line will still remain connected to the program station over the jack J', however, until the plug P' is withdrawn from the jack J'. This will ordinarily take place at the end of the contract period where a definite period of service is previously arranged for, otherwise the subscriber may have the connection to the

program station taken down by calling the regular operator at the jack J in the same manner as when a telephone call is initiated with the program equipment still connected.

5 The operator, upon being informed that the program connection is desired to be taken down, will inform the program operator at the jack J', who will at once withdraw the plug P' from the jack J' and restore the 10 circuits to normal.

Fig. 2 illustrates a modified arrangement in which the program circuit is immediately 15 cut through to the subscriber's line and the line disconnected from the regular switch-board equipment as soon as the plug of the program cord is inserted in the jack at the special multiple, regardless of whether or not the subscriber has hung up his receiver or the cord C disconnected. The general 20 arrangement of the apparatus is similar to that of the apparatus disclosed in Fig. 1 and the detailed differences will be clear from a description of the operation of the circuit which is as follows.

25 Assuming that the subscriber desires to receive the entertainment service, the receiver at station A will be removed from the switchhook, thereby energizing the marginal line relay LR, which completes a circuit for the line lamp. The operator then inserts the plug P of the cord C in the jack J, thereby energizing the cut-off relay COR, which disconnects the line relay LR, and extinguishes the line lamp. Upon ascertaining 30 that a program connection is desired, the operator may call the program operator at the special position over a call wire, notifying her to insert the plug P' of the cord circuit C' leading to the desired program 35 station in the jack J' of the line L. Upon inserting the plug P' in the jack J', a circuit over the high resistance relay 12 is completed from ground, through the winding of said relay, over the sleeve contacts 40 of the jack J' and the plug P', over the lower back contact of relay 12', right-hand back contact of slow release relay 25, back contact of marginal relay 26 and through the winding of relay 26 to battery. Marginal 45 relay 26 will not be energized in series with the high resistance relay 12. Relay 12, on the other hand, will not be energized when in series with the high resistance winding of the relay COR', but the latter relay is short-circuited during the condition 50 above described, over the contacts of relay 12' and relay 25. Therefore, the relay 12 is energized and disconnects the line L from the jack J and connects it to the jack J' so 55 that the program station is now associated with the line. The relay 12 also completes a circuit over its lower front contact for the slow release relay 27. The relay 27 will 60 not be energized as long as the cut-off relay COR is energized because its winding is

short-circuited over its back left-hand contact and over the right-hand front contact of the cut-off relay COR. Assuming, however, that the operator has withdrawn the plug P from the jack J, the cut-off relay 70 COR will be deenergized and the short-circuit removed from the winding of the slow release relay 27, which will be energized to apply a busy tone to the sleeve of the jack J over its right-hand front contact. The 75 circuit from the program station is now cut through to the subscriber's line.

As soon as the circuit from the program station to the subscriber's line is completed, as previously described, an energizing circuit for the marginal relay LR' and the special relay SR' will be completed through the subscriber's set, and both of these relays will be energized as well as the relay 17 of the subscriber's set, provided the subscriber 80 has not already hung up. The latter relay, by energizing relay 18, maintains the loud speaking receiver and associated equipment disconnected from the line independently of the key K. The energization of the marginal relay LR' maintains a short circuit about the winding of the relay 25, so that the latter relay is not energized by the special relay SR'. The special relay SR' completes an energizing circuit for the relay 28, 85 however, over a circuit from ground through the right-hand front contact of relay SR', winding of relay 28, left-hand back contact of relay 25 and over the right-hand front contact of relay LR' to battery. Relay 28, upon being energized, completes a short circuit for the relay COR' over its 90 front contact independently of the right-hand back contact of the slow release relay 25. The subscriber may now actuate the key 95 K and thereafter hang up his receiver. Upon hanging up the receiver, the relay 17 will be deenergized and the loud speaker 11 and associated apparatus will be connected to the line over the contacts of the key K. The marginal relay LR' will now be released 100 because of the high resistance path through the polar relay PR and will remove the short circuit from the winding of the slow release relay 25. The special 105 relay SR' will, however, remain energized in series with the high resistance winding of the polar relay PR and over its right-hand front contact completes a circuit through the windings of relays 28 and 25 in 110 series so that both relays are energized. The short circuit about the winding of the cut-off relay COR', which is opened by the energization of the relay 25, is closed at another point, however, by the front contact 115 of relay 28 so that the relay COR' is not energized. With the circuit in this condition the transmission from the program circuit passes directly over the line L to the subscriber's station and operates the loud 120 speaker 11. The circuit from the program 125 station to the subscriber's line is now cut through to the subscriber's line.

speaking receiver 11. The direction of current flow through the windings of the relays LR' and SR' is, of course, in such a direction as to prevent the operation of the polar relay PR.

If, while the line is thus in use, a sufficiently urgent call should come into the central switching office for the line L, the operator at the jack J may disregard the busy tone 10 on the sleeve of the jack and insert the plug of the cord C in the jack, thus operating the cut-off relay COR. The cut-off relay at its right-hand front contact connects ground over the left-hand front contact of the slow release relay 27 to the sleeve of the jack J', thereby short-circuiting the winding of the relay 12. The relay 12 is thereby deenergized and disconnects the line L from the jack J' and again connects it to the jack J. Since the sleeve of the jack J' is now directly connected to ground, the marginal relay 26 is energized over a circuit from battery, through the winding of said relay, over the back contact of said relay, over the front contact of relay 28, lower back contact of relay 12', sleeve conductors of the plug P' and the jack J' to ground. Relay 26, upon being energized, at its left-hand contact opens the short circuit path about the winding of the relay COR', which is at once energized in series with the relay 26 to connect battery to the disconnect lamp 30 and to the winding of the relay 12'. Relay 12' disconnects the program station from the plug P' of the cord C' and the disconnect lamp 30 indicates to the operator at the program multiple that the cord circuit C' should be disconnected from the jack J'. The relay 12', by opening the trunk circuit, causes the relay SR' to be deenergized, thus restoring the relays 25 and 28 to normal. As soon as the operator withdraws the plug P' the circuit through the relays COR' and 26 is opened, thereby causing the armatures of these relays to fall off. As a consequence, the circuit of the relay 12' is opened and the circuit is restored to normal.

In the meantime, as soon as the relay 12, by falling off, connected the line L to the jack J, the direct current through the cord circuit C passes over the line L in such a direction as to actuate the polar relay PR, which in turn completes a circuit of the relay 16 and disconnects the loud speaking receiver 11 from the transformer 14. The subscriber at station A, in response to a ringing signal, removes his receiver from the switchhook, thereby energizing relay 17, which in turn completes a circuit for the relay 18 to disconnect the receiver 11 and transformer 14 from the line circuit independently of the key K. At the termination of the conversation, the subscriber at station A may signal the operator at the jack J

by manipulating his switchhook and, upon again getting the attention of the operator, may ask to have the program connection restored in the same manner as described in connection with the original setting up of 70 the program connection.

If, while the program connection is set up and in operation, the subscriber at the station A should, for any reason, desire to make an ordinary telephone call, he will remove his receiver from the switchhook, thereby reducing the resistance through the circuit of the relays LR' and SR' so that the marginal relay LR' is operated as well as the relay SR'. The relay LR' completes 75 a circuit for the relay 12' from battery, over the front contact of the relay LR', left-hand front contact of the relay 25 and through the winding of the relay 12' to ground. The relay 12' disconnects the program station 80 from the plug P' and hence from the line L. At its lower contact the relay 12' opens a short circuit about the winding of the relay COR', which is energized and connects battery to the disconnect lamp 30 and 85 also the relay 12', which will now be held up independently of the contact of the relay LR', which falls off upon the opening of the cord circuit by the relay 12'. The inclusion 90 of the high resistance of the relay COR' in the sleeve circuit causes the marginal relay 12 to fall off and connect the line L to the jack J. The operator at the program multiple, upon observing the disconnect signal, will withdraw the plug P' from the jack J' and restore the apparatus of the cord circuit C' to normal. In the meantime, the connection of the line L to the jack J over the contacts of the relay 12 causes the 95 energization of the line relay LR, thereby 100 causing the line lamp to glow and indicate to the operator at the answering jack J that a connection is desired. The telephone connection will now be established in the usual manner. At the end of the conversation, the 110 subscriber may, by calling the operator at the jack J, order the program connection re-established in the manner already described.

If, while the program circuit is in operation, the subscriber desires the program 115 connection taken down, he may simply restore the key K to normal, thereby disconnecting the receiving apparatus from the line and opening the line circuit. The relay SR' at the cord circuit C' will be at once 120 deenergized and will open a circuit of the relays 28 and 25. Relay 28 immediately falls off and opens a short circuit about the cut-off relay COR' before the alternative short circuit is completed over the back contact of the relay 25, the latter relay being 125 slow to release. The relay COR' is consequently energized and connects battery to the disconnect lamp 30 and the relay 12'. The relay 12' disconnects the program station 130

from the plug P' and hence from the line L, and at its lower contact opens the short circuit about the relay COR', independently of either the relay 28 or 25, so that when the latter relay deenergizes the relay COR' will still remain energized. The operator, upon observing the disconnect signal, will withdraw the plug P', thereby deenergizing the relay COR' and the relay 12' to restore the cord circuit to normal. The relay 12 is also deenergized when the sleeve circuit is opened by withdrawing the plug P' and establishing the normal connection from the line L to the answering jack J.

Fig. 3 shows an arrangement adapted for use in connection with step by step machine switching offices. The circuit of Fig. 3 is so arranged that the subscriber may dial a certain code number when he wishes to receive the program service and will thereby be connected by the mechanical switches to terminals of the multiple bank, which are connected through a transformer 13 to the program station D, as indicated. Different code numbers may be assigned to different program trunks and the subscriber may thus elect any particular program. Relays LR' and SR' are connected with the tip and ring conductors of the selector bank, the former being marginal and operated only through the low resistance of the subscriber's set when the receiver is off the hook. Auxiliary relays 31 and 32 are also provided for controlling the busy condition of the sleeve circuit and for performing certain functions incidental to the release of the connection. Further details of the circuit will be clear from a description of the operation which is as follows.

Assuming that the subscriber at station A desires a connection to the program station, the receiver will be removed from the switchhook and the dial 19 will be manipulated in a well known manner to operate the step by step switching machinery to connect the subscriber's line L to the tip and ring conductors of the terminal bank, which are connected to the program station D through the transformer 13. As soon as this connection is established the relays LR' and SR' are both energized over the line circuit L and through the low resistance of the subscriber's set 10. Relay LR' at its upper front contact short-circuits the winding of the relay 31 over the right-hand back contact of said relay 31 to prevent said relay from being energized over the lower front contact of relay SR'. Ground is connected over the upper contact of the relay SR' and over the back contact of the relay 32 to the sleeve conductor to hold the selector and to prevent other selectors from making connection to the selected terminals of the selector bank.

After dialing the code for establishing the

connection just described, the subscriber will operate his connecting key K and hang up his receiver. The relay LR', being marginal, will not be energized through the high resistance of the polar relay PR but the relay SR' will remain energized. Relay LR', upon being released, removes the short circuit from the winding of the relay 31, which is at once energized and connects ground to the sleeve circuit over the back contact of the relay 32 independently of the relay SR'. The connecting key K at the subscriber's station having connected the loud speaking receiver 11 to the line through the transformer 14, the information or the like transmitted from the station D will be transmitted through the transformer 13, through the machine switching connection and over the line L to operate the loud speaking receiver 11. The relay PR is not operated over the program connection because of the direction of current flow supplied through relays LR' and SR'.

When the subscriber desires to terminate the program connection he simply restores the connecting key K, which releases the relay SR', thereby removing ground from the sleeve terminal over the upper front contact of the relay SR' and opening the circuit of the relay 31, which falls off and disconnects ground from the sleeve terminal over its left-hand contact. The mechanical switches are at once released and the apparatus is all restored to normal. If, instead of disconnecting the program station by restoring the connecting key, the subscriber desires to make an ordinary telephone connection while the program connection is still established, the subscriber simply removes the receiver from the switchhook, thereby energizing relay LR' in addition to the relay SR' and also completing the circuit for the relay 17 at the subscriber's station. The relay 17 closes the circuit of the relay 18 to disconnect the loud speaking receiver and associated apparatus in the same manner as described in connection with the previous circuits. The energization of the relay LR' connects battery over the upper front contact of said relay and over the right-hand front contact of relay 31 to the winding of the relay 32, which is energized and disconnects ground from the sleeve conductor of the selector bank, thus releasing the step by step switches in a well known manner. As soon as the step by step switches, in releasing, open the circuits of the tip and ring conductors, relays SR' and LR' are deenergized, thereby opening the circuits of the relays 31 and 32, which are restored to normal. The line switch (not shown) associated with the line L will now seize a selector trunk in the same manner as if the receiver had just been removed from the hook for the first time and the

subscriber may manipulate his dial to obtain the connection desired. With this arrangement, the line will test busy because of the ground connection through the sleeve 5 and all incoming calls to the subscriber will be excluded so long as the program service is being received.

It will be obvious that the general principles herein disclosed may be embodied in 10 other and different organizations widely different from those illustrated without departing from the spirit of the invention as defined in the appended claims.

What is claimed is:

15 1. In a telephone system, a plurality of telephone lines terminating at a central office at one end and a subscriber's station at the other, a telephone set at each subscriber's station, an operator's position at 20 the central office having switching means whereby any one of said lines may be interconnected with another telephone line for telephonic intercommunication, a program transmitting station, connections independent of said operator's position extending 25 from a plurality of lines to a second operator's position, and switching means at said second operator's position for individually interconnecting a plurality of said 30 lines to said program station at the same time over said connections.

2. In a telephone system, a telephone line terminating at a central office at one end and a subscriber's station at the other, a telephone set at the subscriber's station, an operator's position at the central office having switching means whereby said line may be interconnected with other telephone lines for telephonic intercommunication, a program transmitting station, a second operator's position, switching means thereat for interconnecting said program station with said line, and means to disconnect said line at said second operator's position from the 45 switching means at said second operator's position when a connection is established to said line through said first operator's position.

3. In a telephone system, a telephone line 50 terminating at a central office at one end and a subscriber's station at the other, a telephone set at the subscriber's station, an operator's position at the central office having switching means whereby said line may be interconnected with other telephone lines for telephonic intercommunication, a program transmitting station, a second operator's position, switching means thereat for interconnecting said program station with said line, means to disconnect said line from the switching means at said first operator's position when said program station is connected to said line through said second operator's position, and means responsive to 55 an incoming call at said first operator's posi-

tion to disconnect said line from said second operator's position and again connect it to said first operator's position.

4. In a telephone system, a telephone line terminating at a central office at one end and a subscriber's station at the other, a telephone set at the subscriber's station, an operator's position at the central office having switching means whereby said line may be interconnected with other telephone lines 70 for telephonic intercommunication, a program transmitting station, a second operator's position, switching means thereat for interconnecting said program station with said line, means to disconnect said line from the switching means at said first operator's position when said program station is connected to said second operator's position, and means responsive to a call outgoing from said line to disconnect said line from said second operator's position and again connect it to said first operator's position.

5. In a telephone system, a telephone line terminating at a central office at one end and in a subscriber's station at the other, a telephone set at said subscriber's station, program receiving means at said subscriber's station, an operator's position at the central office having switching means for interconnecting said line with other telephone lines for telephonic intercommunication, a program transmitting station, a second operator's position having switching means thereat for interconnecting said program station with said line, and means to connect said program receiving means at the subscriber's station with said line and said program station at the central office with said line over the switching means at said second operator's position when the line is not being used for ordinary telephonic purposes.

6. In a telephone system, a telephone line terminating at a central office at one end and in a subscriber's station at the other, a telephone set at said subscriber's station, program receiving means at said subscriber's station, an operator's position at the central office having switching means for interconnecting said line with other telephone lines for telephonic intercommunication, a program transmitting station, a second operator's position having switching means thereat for interconnecting said program station with said line, means to connect said program receiving means at the subscriber's station with said line and said program station at the central office with said line over the switching means at said second operator's position when the line is not being used for ordinary telephonic purposes, and means for disconnecting said line from said first operator's position when a connection is established to said second operator's position.

7. In a telephone system, a telephone line terminating at a central office at one end

and in a subscriber's station at the other, a telephone set at said subscriber's station, program receiving means at said subscriber's station, an operator's position at the central office having switching means for interconnecting said line with other telephone lines for telephonic intercommunication, a program transmitting station, a second operator's position having switching means thereat for interconnecting said program station with said line, means to connect said program receiving means at the subscriber's station with said line and said program station at the central office with said line over the switching means at said second operator's position when the line is not being used for ordinary telephonic purposes, means for disconnecting said line from said first operator's position when a connection is established to said second operator's position, and means responsive to an incoming call to disconnect said line from the switching means at said second operator's position and again connect it to the switching means at said first operator's position.

8. In a telephone system, a telephone line terminating at a central office at one end and in a subscriber's station at the other, a telephone set at said subscriber's station, program receiving means at said subscriber's station, an operator's position at the central office having switching means for interconnecting said line with other telephone lines for telephonic intercommunication, a program transmitting station, a second operator's position having switching means thereat for interconnecting said program station with said line, means to connect said program receiving means at the subscriber's station with said line over the switching means at said second operator's position when the line is not being used for ordinary telephonic purposes, means for disconnecting said line from said first operator's position when a connection is established to said second operator's position, and means responsive to a call outgoing from said line for disconnecting said line from the switching means at the second operator's position and again connecting it to the switching means at said first operator's position.

9. In a telephone system, a telephone line terminating at a central office at one end and a subscriber's station at the other end, switching points at which other lines terminate, other switching points to which a program transmitting station is connected, link circuits for interconnecting lines in pairs through said first mentioned switching points or for interconnecting a plurality of lines to said program station through said second

mentioned switching points, and means responsive to an incoming call for said first mentioned line when said line is connected to said program station for disconnecting the line from the program station and connecting it to the calling telephone line.

10. In a telephone system, a telephone line terminating at a central office at one end and a subscriber's station at the other end, switching points at which other lines terminate, other switching points to which a program transmitting station is connected, link circuits for interconnecting lines in pairs through said first mentioned switching points or for interconnecting a plurality of lines to said program station through said second mentioned switching points, and means responsive to a call outgoing from said first mentioned line when the line is connected with said program station for disconnecting the line from said program station and connecting it to the called line.

11. In a telephone system, telephone lines terminating at a central office at one end and a subscriber's station at the other, a telephone set at each subscriber's station, an operator's position at the central office having switching means whereby any one of said lines may be interconnected with another telephone line for telephonic communication, a program transmitting station, a second operator's position at which said program station may be connected to a plurality of said lines, means to signal the operator at said second position, and means to defeat the connection of a given line through said second position when said line is connected to another line at said first position.

12. In a telephone system, telephone lines terminating at a central office at one end and a subscriber's station at the other, a telephone set at each subscriber's station, an operator's position at the central office having switching means whereby any one of said lines may be interconnected with another telephone line for telephonic intercommunication, a program transmitting station, a second operator's position at which said program station may be connected to a plurality of said lines, means to signal the operator at said second position to disconnect the program station from a given line, and means to defeat the connection of said given line through said second position when said line is connected to another line at said first position.

In testimony whereof we have signed our names to this specification this 10th day of November 1922.

JOHN F. TOOMEY.
HENRY E. PHELPS.
